CLAIM

The ornamental design for a rake, as shown and described.

DESCRIPTION

FIG. 1 is a perspective view of the rake;

FIG. 2 is a front view of the rake;

FIG. 3 is a back view of the rake;

FIG. 4 is a right side view of the rake;

FIG. 5 is a left side view of the rake;

FIG. 6 is a bottom view of the rake; and,

FIG. 7 is a top view of the rake.

The broken lines in the drawings illustrate portions of the rake and form no part of the claimed design.

1 Claim, 5 Drawing Sheets
